UNITED STATES PATENT OFFICE.

WILLIAM KOWALSKI, OF CHICAGO, ILLINOIS.

SAFETY DEVICE FOR MINING-CARS.

1,159,050.

Specification of Letters Patent.

Patented Nov. 2, 1915.

Application filed February 16, 1915. Serial No. 8,677.

To all whom it may concern:

Be it known that I, WILLIAM KOWALSKI, a citizen of the United States, residing at Chicago, in the county of Cook and State 5 of Illinois, have invented new and useful Improvements in Safety Devices for Mining-Cars, of which the following is a specification.

This invention relates to mining cars, and 10 it has particular reference to that class of cars which are operated on an inclined plane, the same being lowered by gravity and raised by means of a cable that is wound on a drum operated by suitable 15 power at the mouth of the mine.

The invention has particular reference to 20 safety devices employed in connection with cars of this type for the purpose of checking the same and preventing gravitational device 25 in case of breakage or injury to the hoisting apparatus; such safety device including a third rail interposed between the track rails and grab means carried by the car and coöperating automatically with such third rail in case of necessity.

The invention has for its object to simplify and improve the safety mechanism and 30 to produce a hook which will unfailingly operate in conjunction with the third rail when an emergency arises.

A further object of the invention is to produce a simple and efficient construction whereby the hook may be restored and maintained in position for coupling the car with 35 other cars until the beginning of the ascent or descent, as the case may be.

With these and other ends in view which 40 will readily appear as the nature of the invention is better understood, the same consists in the improved construction and novel arrangement and combination of parts which will be hereinafter fully described and particularly pointed out in the claim.

In the accompanying drawings has been 45 illustrated a simple and preferred form of the invention, it being, however, understood that no limitation is necessarily made to the precise structural details therein exhibited, but that changes, alterations and modifications 50 within the scope of the claim may be resorted to when desired.

In the drawings,—Figure 1 is a plan view 55 of a car frame equipped with the invention. Fig. 2 is a longitudinal sectional view showing the device in position for coupling with

other cars. Fig. 3 is a side elevation showing the locking dog disengaged from the ratchet. Fig. 4 is a longitudinal sectional view showing the safety device in operation.

Corresponding parts in the several figures 60 are denoted by like characters of reference.

The frame of the improved car is composed of side members 15 and end members 16, the latter being rounded, as shown. Said side and end members are preferably 65 constructed of angle steel of proper dimensions to enable the frame to resist any strain to which it will be subjected, reinforcing blocks or bumper blocks 17 being used at the corners of the frame. The mechanism of 70 the safety device is used at each end of the car frame, but as the construction of the two ends is identical, the description of one will apply to both ends.

The end member 16 at each end of the 75 car frame is apertured for the passage of a draft hook or coupling hook 18 which is 80 slideable longitudinally through the aperture 19, the latter being sufficiently large to enable the draft hook to be tilted in a vertical 85 plane. The draft hook is connected with one end of a draw bar 20, the other end of which is notched vertically to produce two ears 21.

Supported for oscillation in the side members 15 adjacent to the blocks 17 is a rock shaft 22 on which the safety hook 23 is firmly secured. Said hook which normally extends forwardly with respect to the rock shaft 22 has a reversely turned bill 24 which 90 is pivotally supported between the ears 21 of the draw bar by means of a transverse pin or pivot member 25. The rock shaft 22 is provided with radial arms 26 which are connected by means of springs 27 with similar arms 28 extending radially from a shaft or cross bar 29 which is rigidly mounted 95 between the side members 15 in rear of the rock shaft 22. The tension of the springs 27 will be normally exerted to rock the shaft 100 22 to throw the safety hook 23 in a downward direction, causing the bill thereof to engage the teeth or ratchets 30 of the safety rail 31 which is located between the track rails 32. It will be seen that the hook 23 105 and the draw bar 20 may be regarded as constituting a toggle and that stress in a forward direction on the draft hook 18 will tend to straighten out the arms of said toggle, thus counteracting the influence of 110

the springs 27 and sustaining the hook 23 normally out of engagement with the teeth 30.

As the hook 18 is not always under stress or tension it is desirable to provide special means for the purpose of temporarily maintaining the safety hook out of engagement with the teeth of the safety rail. To this end the rock shaft 22 is provided with a ratchet wheel 33 engaged by a dog or pawl 34, whereby the rock shaft may be held securely when the springs 27 are under tension. Said rock shaft is preferably provided with a wrench seat 35 for the reception of a crank whereby it may be turned for the purpose of placing the springs under tension. In this manner the safety hook may be positively maintained out of engagement with the safety rail when stress is not exerted on the hook 18. As soon as said hook is placed under tension by the action of the hoisting mechanism the dog 34 is to be disengaged from the ratchet wheel 33.

From the foregoing description, taken in connection with the drawings hereto annexed, the operation and advantages of this invention will be readily understood by

those skilled in the art to which it appertains. The improved safety device is simple in construction, inexpensive and thoroughly effective for the purposes for which it is provided.

Having thus described the invention, what is claimed as new, is:—

In a device of the class described, a rock shaft carrying a safety hook, a draft member pivotally connected with said hook and combining therewith to form a toggle, arms extending radially from the rock shaft, a stationary bar or shaft supported in parallel relation to the rock shaft and having radial arms, and springs connecting the last mentioned arms with the radial arms of the rock shaft, in combination with a ratchet wheel on the rock shaft, a dog engaging said ratchet wheel, and a wrench seat on the rock shaft to receive a crank whereby it may be turned to place the springs under tension.

In testimony whereof I affix my signature in presence of two witnesses.

WILLIAM KOWALSKI.
